Bucket or container for holding liquid or foodstuffs having an annular rubber shield for insulating the contents thereof and protecting the exterior of the bucket.

Provided further whether or not said annular rubber shield is made of resilient rubber, and such shield is not subject to destruction or melting when exposed to heat, and is not subject to sudden contraction or expansion when exposed to cold, and is not subject to sudden weight reduction, and such shield is made of flexible material which will not readily damage, break and become separated from the bucket.

UNITED STATES PATENT OFFICE

1,985,558

PROTECTOR FOR LUNCH BUCKETS

James H. Alexander, Staunton, Ill.

Application February 26, 1934, Serial No. 713,044

1 Claim. (Cl. 220—69)

My invention relates to a protector for lunch buckets.

The object of my invention is to provide a flexible protector fitting snugly on the exterior of a bucket as an insulation for the contents thereof and a shield for the bucket.

A further object of my invention is to provide a resilient protector snugly fitting on the lower portion of a bucket and having a plurality of horizontally disposed projections simulating bands and to function as a cushion against sudden contact with other objects.

A still further object of my invention is to provide a flexible protector preferably made of rubber to engage snugly about the exterior of a bucket and retained by resilient tension thereon, and removable for application to other buckets.

A still further object of my invention is to provide a flexible rubber protector to receive and envelop the lower portion of a bucket and having an exhaust port to avoid compression during the process of inserting the bucket, the port adapted to normally close itself when compression is released, and the said port to be sealed by the application of rubber cement to avoid intake of air as a further retainer for the shield to the bucket.

A still further object of my invention is to provide a protector functioning as an insulator, in which case sponge rubber may be employed, and having a plurality of recesses arranged for the bottom to avoid direct contact of the entire surface thereof when seated.

These and other objects will hereinafter be more fully explained, reference being had to the accompanying drawing forming a part of the specification, and in which like characters will apply to like parts in the different views.

Referring to the drawing:

Fig. 1 is an elevation of a bucket with my protector applied, and being partly in section for convenience of illustration.

Fig. 2 is an inverted view of the protector showing the external form of the bottom.

Fig. 3 is an enlarged fragmentary section of the center portion of the bottom illustrating the application of an exhaust tube insertable within the exhaust port.

Fig. 4 is an enlarged cross section thru one of the ribs taken on line 4—4 in Fig. 2.

Fig. 5 is an enlarged sectional view modifying the ribs in form with respect to cross section.

Fig. 6 is a modified construction of the wall and bottom of the protector.

To clearly set forth my invention, attention is directed to the specific disclosure in which I

have provided for a dinner bucket 1, a protector comprising an annular wall 2 having a bottom 3, all to engage snugly with the bottom and portion of the side wall of the bucket. The said protector is preferably made of resilient rubber compacted in texture, but not confined to such alone as sponge rubber may be employed and other variations with respect to texture. To avoid excess quantity to accomplish the feature of protection against sudden contact with other objects and additional tension to retain the protector on the bucket, I have provided an annular extension 4 near the top and bottom of the structure, and a centrally disposed extension 5, all integral with the wall. The bottom has a plurality of ribs 6 radially extending from a disc like extension 7 to an annular portion 8. The last said portion is on a plane with the center portion and the outer extension of the ribs, in other words, the body portion of the bottom is depressed at a greater depth adjacent the center portion and diminishing at the plane of the said annular portion 8, by which means the bottom of the bucket is protected by the increased thickness of the bottom portion of the protector, and furthermore a liberal portion of the said bottom is spaced from contact when the bucket is normally seated. If placed on a smooth surface, the depressed portions will function as air spaces.

Centrally positioned in the extended portion 7 is an exhaust port 9 preferably punctured by a pointed instrument and adapted to close when the instrument is withdrawn, but convenient for the insertion of a tube 10 as shown in Fig. 3 functioning as an exhaust at the time of inserting the bucket within the walls of the protector. To assist the insertion of the tube, I have arranged a funnel 11 at the exterior entrance thereof. It will be understood that when the said protector is applied to a bucket, the wall and bottom snugly engaging therewith, then the tube is removed and the puncture sealed by the application of rubber cement or the like.

As a modification, I have provided a fiber lining 12 for the protector. The said lining extending over the bottom and side wall upward to a spaced distance from the top thereof, by which means added insulation is provided, and such other modifications may be employed as lie within the scope of the appended claim, and having fully described my invention, what I claim as new and desire to secure by Letters Patent is:

In a protector for buckets of the class described, comprising an annular rubber wall having an upper, a lower and an intermediate extension ex-

5 internal of the wall and a radially ribbed bottom therefor, the ribs integrally joined to the bottom and an annular portion as closing means for the space between the ribs to avoid circulation of air beneath the bottom, a flexible fiber lining as an insulation for the bottom and side wall to near the upper extremity thereof but sealed against

by an inward extension and downward a spaced distance from the point of the upper extension of the wall, by which means the fiber lining is protected against fluid absorption when a bucket is placed within the said wall.

JAMES H. ALEXANDER.

and a "holy spirit" or "spiritual gift" of "prophesy" to be received with the baptism and to be exercised after one has received it. According to the definition of a prophet given in the New Testament, a prophet is one who is sent by God to speak in his name. The New Testament also speaks of "prophetic gifts" which are given to the church for the edification and encouragement of the members. These gifts are said to be given to the church for the edification and encouragement of the members.

and reorganized into the 10th Cavalry, the 11th and 12th Cavalry being consolidated into the 11th Cavalry, and the 13th Cavalry being disbanded.

the results were not significant, and the effect of the intervention was not significant. The results of the study are presented in Table 1.
